UNITED STATES PATENT OFFICE.

JOHN JOSEPH PETERS, OF OELWEIN, IOWA, ASSIGNOR OF ONE-HALF TO NORMAN B. AKITT, OF OELWEIN, IOWA.

LATERAL TAKE-UP FOR DRIVING-BOXES.

1,397,110.

Specification of Letters Patent.

Patented Nov. 15, 1921.

Application filed July 12, 1920. Serial No. 395,772.

To all whom it may concern:

Be it known that I, JOHN JOSEPH PETERS, a citizen of the United States, and a resident of the city of Oelwein, county of Fayette, 5 and State of Iowa, have invented certain new and useful Improvements in Lateral Take-Ups for Driving-Boxes, of which the following is a specification.

My invention relates to new and useful 10 improvements in lateral take-up for driving boxes, and has for its object the provision of a device of this class, which will be simple in structure, economic in manufacture and highly efficient in use.

15 Other objects will appear hereinafter.

The invention consists in the combinations and arrangements of parts hereinafter described and claimed.

The invention will be best understood by 20 reference to the accompanying drawings forming a part of this specification, and in which,

Figure 1, is a sectional view of the invention as applied to a driving box mounted on 25 an axle,

Fig. 2, is a view similar to Fig. 1, showing the invention in operative position,

Fig. 3, is a side elevation of the device.

Between the outside face of a driving box 30 and the hub of the wheel which is used on locomotives, freight cars, and the like, there is a certain amount of clearance or space which is known as the lateral. In operation, the hub of the wheel frictionally engages the face of the driving box and after 35 a time the face of the driving box becomes worn, so that this lateral or clearance has increased. When the lateral clearance between the face of the hub and the face of the driving box is $\frac{3}{8}$ of an inch on each side, under the present law it is necessary to withdraw the car from operation until the driving box is refaced, or until some provision is made for bringing the lateral within the 40 $\frac{3}{8}$ of an inch limit. Various ways have been devised for producing this effect, particularly of which is the method of refacing the driving boxes with a brass member. In order to do this, it is necessary that the 45 truck be removed from the car and the driving box be removed from the axle. It is apparent that this is a round-house job and necessitates the removal of the car from service for considerable time.

50 I have provided a means for taking up

this lateral and reducing the clearance to the necessary space without causing the removal of the trucks or the binder from the car, and without necessitating the removal of the car from service.

60 The driving box 7 is usually mounted in a frame 8. Embracing one side of the frame 8 is a channel shaped shoe 9, the face of which is adapted to engage against one of the sides of the driving box. A channeled 65 wedge 10 is provided at the opposite side of the frame adapted to engage the opposite side of the driving box for securely mounting the same in the frame. As shown in Fig. 3, the wedge 10 is provided with a bevel surface at its inner side which coöperates with the inclined side wall of the frame, and serves as a wedge to bind the driving box within the frame. A bolt 11 is threaded into the wedge 10 and an adjustment of the wedge 70 is thus brought about to tightly bind the driving box as will be readily understood. As shown in Fig. 3, the bolt 11 extends downwardly through the binder 12 of the frame. The axle 13 is journaled in the driving box and mounted at each end thereof is a wheel 14. In constructing my invention, I form the members 9 and 10 in such a manner that the channel is wider than the frame with which they are designed for use. Positioned between the channel and the frame so as to make a snug engagement are plates 15 and 16. In Fig. 1, I have shown these plates carried idly in the shoe 9 and the wedge 10 and it will be noticed that they are positioned between the inner side of the frame 8 and the channel of the shoe or wedge. Each of the plates is provided with a recess 75 17 in which engages the legs of a U-shaped member 18, said member 18 being secured to the side of the frame by a suitable bolt or lag screw 19. When the lateral wear has become greater than is allowed by law, the plate 15 or 16 as the case may be, may be removed from its position and placed as 80 shown in Fig. 2, namely, between the outside face of the frame 8 and the leg of the shoe or wedge as the case may be. In this manner, the frame remaining stationary, the driving box is carried outwardly relatively 85 thereto, a distance equal to the width of the members 15 and 16. In order to force the driving box outwardly, a jack may be engaged between each of them and the operation 90 thereby easily carried out.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 10 the appended claims.

Having described my invention, what I claim as new and desire to secure by Letters Patent is:—

1. In combination, a driving box mountable in a frame; wear members insertible between said frame and said driving box; and means engaging between one side of said frame and said wear members and transposable for engagement between said 15 wear members and the opposite side of said frame for shifting said driving box relatively to said frame, substantially as described.

2. In combination, a driving box mountable in a frame; wear members insertible between said frame and said driving box; means engaging between one side of said frame and said wear members and transposable for engagement between said 25 wear members and the opposite side of said frame for shifting said driving box relatively to said frame; and means for securing said means in said engaging positions, substantially as described.

3. In combination, a driving box mountable in a frame; wear members interpositioned between said box and said frame and embracing the same; and means engaging between one side of said frame and said 30 wear members and transposable for engagement between said wear members and the opposite side of said frame for shifting said driving box relatively to said frame, substantially as described.

4. In combination, a driving box mountable in a frame; means for mounting said box in said frame; means for shifting said driving box laterally relatively to said frame; and a bar embracing said frame for 40 securing said shifting means in operative position, substantially as described.

5. In combination, a driving box mountable in a frame; means for mounting said box in said frame; means mountable between said mounting means and said frame for changing the relative position of said box to said frame; and U-shaped members embracing said frame for securing said last mentioned means in operative position, substantially as described.

6. In combination a driving box mountable in a frame; channel members for mounting said box in said frame; adjusting

plates insertible between said frame and said channel members for shifting the driving box laterally in either direction relative to said frame; and angular bars for retaining said adjusting plates in position, substantially as described.

7. In combination a driving box mountable in a frame; an axle journaled in said box; a wheel mounted on said axle and spaced from said box; adjusting plates adapted to be inserted adjacent the frame and the driving box to shift said box toward 70 said wheel to compensate for wear on the outer face of said driving box, substantially as described.

8. In combination a driving box mountable in a frame; means for mounting said box in said frame so as to permit lateral movement with respect thereto; and means engaging said mounting means and said frame for changing the relative position of said box to said frame to compensate for wear on said box, substantially as described.

9. In combination a driving box mountable in a frame; means for mounting said box in said frame so as to permit lateral movement with respect thereto; means engaging said mounting means and said frame for changing the relative position of said box to said frame to compensate for wear on said box; and means for retaining said 90 engaging means in operative position, substantially as described.

10. In combination a driving box mountable in a frame; a shaft projected through said driving box; a wheel mounted on said shaft and spaced from said driving box; means for mounting said box in said frame so as to permit lateral movement with respect thereto; and means engaging said mounting means and said frame for changing the relative position of said box to said 100 frame to compensate for wear on said box, substantially as described.

11. In combination a driving box mountable in a frame; a shaft projected through said driving box; a wheel mounted on said 110 shaft and spaced from said driving box; means for mounting said box in said frame so as to permit lateral movement with respect thereto; means engaging said mounting means and said frame for changing the relative position of said box to said frame to compensate for wear on said box; and means for retaining said engaging means in operative position, substantially as described.

In testimony whereof I have signed my 120 name to this specification in the presence of two subscribing witnesses.

JOHN JOSEPH PETERS.
